UNITED STATES PATENT OFFICE.

WILLIAM E. BEASLEY, OF GREENVILLE, SOUTH CAROLINA, ASSIGNOR TO DRAPER CORPORATION, OF HOPEDALE, MASSACHUSETTS, A CORPORATION OF MAINE.

TAKE-UP MECHANISM FOR LOOMS.

Application filed November 17, 1922. Serial No. 601,598.

To all whom it may concern:

Be it known that I, WILLIAM E. BEASLEY, a citizen of the United States, and resident of Greenville, in the county of Greenville 5 and State of South Carolina, have invented an Improvement in Take-Up Mechanisms for Looms, of which the following description, in connection with the accompanying drawings, is a specification, like characters 10 on the drawings representing like parts.

This invention relates to take-up mechanisms for looms through the instrumentalities of which the cloth is taken-up as it is woven.

15 It is now the general practice to lead the cloth over a take-up roll which is driven through a train of mechanism from a going part of the loom and wind it upon a cloth beam as it is woven. Between the take-up 20 roll and the warp let-off mechanism the warp threads and cloth are held under sufficient tension to present the "fell" of the cloth in proper relation to the beat-up action of the reed and as an element to this 25 end the take-up roll is usually provided with a roughened surface which grips the cloth as the roll is slowly rotated by the positive action of the train of take-up mechanism in timed relation to the cloth production. It happens at times that the take-up 30 action or pull of the take-up roll on the cloth becomes excessive due to various causes, such for instance by the cloth, instead of being delivered directly to the 35 cloth beam, becoming wrapped around the take-up roll or tucked under the part of the cloth leading over the take-up roll. In such instances, regardless of the primary cause of such excessive opposition to rotation of the take-up roll, undue strain is 40 developed in the train of take-up mechanism resulting in some cases in breakage of parts.

One of the objects of the present invention is to overcome this objection and provide 45 a cloth take-up mechanism which will automatically relieve the excessive strain and avoid breakage of parts. An important feature of the invention, therefore, consists of a give-way device which will become 50 automatically effective to interrupt the transmission between the take-up actuator and take-up roll when the strain on the transmission mechanism becomes excessive.

In accordance with the present invention, 55 in the form thereof to be described, when

the take-up roll or transmission mechanism is subjected to such excessive strain that would be liable to cause injury either to the cloth, the warp threads, or transmission mechanism, the give-way device is automatically actuated to relieve the strain, all of which will be made clear from the following description and accompanying drawings of one good practical form of the invention.

In the drawings:

Fig. 1 is a perspective view of sufficient parts of the loom and take-up mechanism to show the invention associated therewith and its manner of operation;

Fig. 2 is a side view showing parts of the loom, take-up mechanism, and one good form of the give-way device in operative and inoperative positions.

The invention is applicable to various 75 types of take-up mechanism many of which are old and well-known, but in the present instance the take-up mechanism comprises a train of gearing between the take-up roll and take-up actuator, and the give-way device is constructed and arranged to operatively disengage at least two of the gears in the train of gearing when excessive strain in the train caused by the pull of the cloth or opposition to rotation of the take-up roll 80 approaches a dangerous point.

In the drawing the loom frame 1 has mounted thereon in the usual bearings, which are omitted for clearness of illustration, the take-up roll 2, shown in the present instance as provided with a roughened surface. In some cases the take-up roll may be of the sand roll type or formed of sheet metal with portions punched or projecting from the roll to engage the cloth with sufficient hold to insure proper take-up action. The cloth 4 passes about the take-up roll and is delivered to the cloth beam 5 upon which it is wound. The cloth beam is shown as driven from the take-up roll against 90 which it is yieldingly held by a rack 6 movable in the guideways 7, and provided with teeth 8 engaged by the teeth of a gear 9, mounted on the rotatable shaft 10. The shaft 10 is normally under the influence of 95 a spring 11 which tends to lift the rack 6 and hold the cloth beam in yielding engagement with the take-up roll, or against the cloth 4 which passes between them. There is nothing new in this arrangement,

and indeed any of the usual means for holding the cloth beam in operative relation with the take-up roll may be employed.

The shaft 12 of the take-up roll has secured thereto as shown the toothed wheel or gear 13 which is operatively engaged by an idle gear 14 mounted on a pin or shaft 15 extending from the loom frame 1.

Mounted on a stud or shaft 16 carried by the loom frame is the large toothed wheel 17, which for identification hereinafter may be termed the "controller pinion", and it is engaged with the gear 14 as shown, the construction being such that upon rotation of the large toothed wheel 17 or controller pinion, rotative movement will be imparted to the gear 13 in the direction of the arrow to take-up the cloth 4 as it is woven.

The stud or shaft 16 upon which the controller pinion is mounted carries a swing frame 18, the lower portion of which at 19 is provided with a slot through which passes the stud or pin 20 on which are mounted for rotative movement the two connected gears 21 and 22. By loosening the nut 23 which holds the stud 20 to the swing arm 18, the gear carrying stud 20 may be adjusted longitudinally of the swing arm 18 towards or from the axis of the controller pinion 17, and thereby provision is made for changing the size of the gears 21 and 22 in accordance with conditions of use.

Mounted upon the stud or dead shaft 24 carried by the loom frame is the pick wheel 25 having teeth 26 which are engaged by a push pawl 27, as shown. The push pawl 27 is pivoted at its lower end portion 28 to one of the lay swords 29 carrying the lay 30 which as usual in looms is given a movement towards and from the front of the loom to beat up the filling.

Secured to the pick wheel 25 or associated therewith on the shaft 24 to rotate with the pick wheel is a gear 31 which normally meshes with or is engaged by the gear 22 mounted on the swing arm 18, and the gear 21 which rotates with the gear 22 meshes with the controller pinion 17, as indicated in Figs. 1, 2.

From the construction described it will be clear that as the pawl 27 rotates the pick wheel step by step during loom operation, movement will be transmitted through the gears 31, 22, 21, and the controller pinion 17, the idler 14 and gear 13 to the take-up roll 2 about which the cloth is passed.

The swing frame 18 is normally under the influence of a spring 32, one end of which is connected to the swing frame at 33 and the other end of which is connected to an adjustable pin 34 carried by the loom frame or some fixed part, the construction being such that under the influence of the spring 32 the swing frame 18 will be yieldingly forced in a direction to maintain the gear

22 in operative engagement with the gear 31 and the gearing of the transmission gears will be operatively rotated to transmit motion from the pick wheel 25 through the train of gearing to the take-up roll.

The swing frame 18 is provided with a stop to limit movement of the swing frame under dictation from the spring 32. In the present instance the swing arm has a lug 35 extending laterally therefrom and an adjustable screw 36 is threaded through the lug to engage the loom frame or a part carried thereby. It is desirable that the adjusting screw 36 be adjusted in such position that when the teeth of the gear 22 are engaged with the teeth of the gear 31 that the stop will act to limit further strain upon the gear teeth of the two gears.

In take-up mechanisms for looms it is usual to provide an actuator for the take-up mechanism and a train of gearing between the actuator and the take-up roll. The character of the actuator and its construction varies in different looms, and any one of the different types of actuators for the take-up may be employed in connection with the present invention. In the present instance, however, the actuator is shown as the pawl 27 operated from one of the lay swords and a holding pawl 37 is employed to prevent backward movement of the pick wheel 25 when the pawl 27 makes its idle stroke.

When the loom is running under normal conditions and the cloth is being taken-up properly as it is woven, the parts are in the position shown by Fig. 1 and by full lines in Fig. 2. When, however, the strain on the cloth becomes excessive or opposition to rotative movement of the take-up roll becomes excessive from any cause, it will act through the gears 13 and 14 to retard or stop rotation of the controller pinion 17, but since the actuator for the take-up mechanism continues in operation, the gears carried by the swing arm 18 will continue to rotate in the direction of the arrow, Fig. 2, and the teeth of the gear 21 will act through the teeth of the now stationary controller pinion to cause the gear 21 to travel along the periphery or teeth of the controller pinion and force to carry the teeth of the gear 22 out of operative relation with the teeth of the gear 31, as shown by the dotted lines in Fig. 2, and thus interrupt the transmission through the train of gearing to the take-up roll.

When the loom attendant has remedied the fault which imparted excessive opposition to rotative movement of the take-up roll so that the controller pinion becomes free to rotate, the spring 32 will act through the swing frame 18 to carry the gears 22, 31 into operative relation and the take-up mechanism will then continue to operate.

It will be noted in the present instance of the invention that the transmission gearing

between the actuator of whatever type and the take-up roll will transmit to the take-up roll its take-up movement, but when excessive resistance is offered to rotation of the take-up roll, the give-way device will automatically interrupt the transmission of movement to the take-up roll, and when the defect has been cured will automatically return the parts to operative relation without 10 danger of breakage of parts or injury to the cloth or warp threads.

What is claimed is:

1. In a take-up mechanism for looms, the combination of the cloth take-up roll for 15 taking up the cloth as it is woven, a controller gear operatively connected to the take-up roll for actuating the latter, an actuator, a transmission gear constantly driven therefrom, a give way gear meshing with the controller gear and normally engaged with the transmission gear, and means for yieldingly supporting the give way gear that it may move about the controller gear and out of engagement with the transmission gear due 20 to its rotation thereby when the controller gear is arrested by undue strain upon the cloth during weaving.

2. In a loom, the combination of the cloth take-up roll, a cloth beam frictionally driven 25 by engagement of the take-up roll with the cloth wound upon the cloth beam, an actuator, a train of gearing between the actuator and cloth take-up roll including a swinging gear for causing the take-up roll to take up 30 the cloth as it is woven, and means rendered automatically effective by undue strain in said train of gearing during weaving for moving the swinging gear into an inoperative position that the take-up roll may remain at rest while the loom continues to run.

3. In a loom, the combination of the take-up roll, an actuator, a train of gearing between the take-up roll and actuator, and a give-way device consisting of a pair of gears 45 normally maintained in mesh with each other and one of which is mounted to move out of mesh with the other gear automatically by undue strain in the gearing between the actuator and take-up roll for operatively disconnecting the take-up roll from the actuator.

4. In a loom, the combination of the cloth take-up roll for taking up the cloth as it is woven, an actuator, a train of gearing between the take-up roll and actuator for causing rotative movement of the take-up roll during weaving, a give-way device in the train of gearing, yielding means normally acting to hold the give-way device in operative position and adapted to be overcome by an abnormal pull of the cloth that the give-way device may operatively disconnect two gears of the train automatically while the loom continues to run.

5. In a take-up mechanism for looms, the

combination of the take-up roll about which the cloth is passed, a train of gearing operatively connected to the take-up roll, a spring normally acting to hold two of the gears of the train of gearing in operative 70 relation, an actuator for transmitting cloth take-up movement to the take-up roll through said train of gearing, and means for supporting one of the spring engaged gears and constructed and arranged to permit the 75 spring engaged gears to automatically become operatively disengaged by an abnormal pull of the cloth while the loom continues to run.

6. In a take-up mechanism for looms, the combination of a take-up roll for taking up the cloth as it is woven, an actuator, a train of gearing between the actuator and take-up roll including a give-way device comprising 80 transmission gearing normally held in operative relation with the train of gearing until the pull of the cloth becomes excessive, and a spring which yields when the pull of the cloth becomes excessive to permit one of the 85 gears of the train of gears to move out of 90 operative engagement with the gear with which it normally co-operates while the loom continues to run.

7. In a take-up mechanism for looms, the combination of the take-up roll, an actuator, 95 a train of gears between the take-up roll and actuator, a give-way carrier on which is mounted transmission gearing of said train of gears, a spring normally acting through the give-way carrier to hold the transmission 100 gears in operative relation and constructed and arranged to yield through excessive resistance to rotation of the take-up roll and permit movement of the give-way carrier for disengagement of the transmission gearing from operative position in the train of 105 gears.

8. In a take-up mechanism for looms, the combination of the take-up roll, an actuator, 110 a train of gearing between the take-up roll and actuator, a swinging give-way carrier on which a gear of the train is mounted, a spring which normally acts to hold the swinging carrier with its gear in mesh with other gears of the train and yieldable when 115 excessive resistance to rotation is encountered by the gears between it and the take-up roll that the gear of the swinging carrier may automatically cause the carrier to move about its axis and interrupt the train of 120 gearing.

9. In a take-up mechanism for looms, the combination of the take-up roll, an actuator, 125 a train of gearing between the take-up roll and actuator, a swinging give-way carrier on which a gear of the train is mounted, a stop for limiting the movement of the carrier in one direction, a spring which normally acts to hold the swinging carrier with its gear in mesh with other gears of the train 130

and yieldable when excessive resistance to rotation is encountered by the gears between it and the take-up roll that the gear of the swinging carrier may automatically cause 5 the carrier to move about its axis and interrupt the train of gearing.

10. In a take-up mechanism for looms, the combination of the take-up roll, an actuator, a train of gearing between the take-up roll 10 and actuator, a movable carrier on which a gear of the train is mounted to be moved by the carrier into and out of mesh with the gear with which it cooperates, and means for yieldingly holding the carrier in position to maintain the gears meshed but movable to disengage the gears when excessive resistance to rotation of the take-up roll is 15 encountered.

11. In a take-up mechanism for looms, the combination of the take-up roll, an actuator, a train of gearing between the take-up roll and actuator, a movable carrier on which a gear of the train is mounted to be moved by the carrier into and out of mesh with the gear with which it cooperates, and means for yieldingly holding the carrier in position to maintain the gears meshed but movable to disengage the gears when excessive resistance to rotation of the take-up roll is encountered, and a stop for limiting the movement of the carrier in the gear meshing direction. 20 25 30

In testimony whereof I have signed my name to this specification.

WILLIAM E. BEASLEY.
